UNITED STATES PATENT OFFICE

WILLIAM S. PRITCHARD, OF DETROIT, MICHIGAN, ASSIGNOR TO MOTOR PRODUCTS CORPORATION, OF DETROIT, MICHIGAN, A CORPORATION OF NEW YORK

WEATHER STRIP

Application filed April 25, 1927. Serial No. 186,517.

This invention relates to weatherstrips and more especially to improvements therein and to an improved means for spacing, supporting and securing the weatherstrip in place.

5 The several objects, advantages and novel details of construction of the invention will be made more apparent as this description proceeds, especially when considered in connection with the accompanying drawings 10 wherein:

Figure 1 is a fragmentary sectional view showing a weatherstrip constructed in accordance with my invention, and

15 Figure 2 is a fragmentary sectional view showing the use of this weatherstrip with a windshield.

Referring now particularly to the drawings wherein like reference characters indicate like parts, it will be noted that I have illustrated a support 10 formed with a rabbet or recess 11 comprising walls 12 and 13. The weatherstrip is adapted to be located and secured in this recess.

The weatherstrip 14 includes a base or laterally extending portion 15 and an upstanding portion 16. The laterally extending portion 15 is provided with a longitudinally extending recess or groove 17. The reference character 18 indicates a securing strip substantially U-shaped in cross section, one leg 19 of which is adapted to engage the groove 17 and interlock therewith while the other leg 20 rests upon the base 12 of the recess or rabbet. The leg 19 also abuts the upstanding portion 16 of the weatherstrip and acts to brace or support the same. The other leg 20 abuts the wall 13 of the rabbet or recess and acts to align and space the weatherstrip within the recess. The strip 18 is secured to the support 10 by means of fastening members such as screws 21. In Figure 8, wherein one of the applications of this improved weatherstrip is illustrated, it will be noted that there is illustrated a windshield 22 provided with a frame 23 provided with an inclined surface 24 adapted to engage the upstanding portions 16 of the weatherstrip as the windshield is closed to deflect the weatherstrip into surface contact with the inclined wall 24. It will be 50 obvious, however, that the herein described

weatherstrip is capable of use in connection with various types of closures such as windshields, windows, doors and the like.

While an embodiment of the invention has been described herein somewhat in detail it will be readily apparent to those skilled in this art that various changes may be resorted to without departing from the spirit and scope of this invention and to this end reservation is made to make such changes as may come within the purview of the accompanying claim.

What I claim as my invention is:—

The combination with a support, of a weatherstrip having a grooved lateral extension mounted upon one wall of said support, a substantially U-shaped retaining strip having one leg engaging in said groove and the other leg spaced inwardly from the end of the extension aforesaid and engageable with the said wall of the support, and means for securing said strip to said support including a fastening element extending through the base of the strip and into the support at a point spaced from the end of the extension whereby upon clamping the strip to the support, the same pivots about the leg engageable with the wall aforesaid to firmly clamp the weatherstrip to the support.

In testimony whereof I affix my signature. 80
WILLIAM S. PRITCHARD.
